UNITED STATES PATENT OFFICE.

LEE P. HYNES, OF CHICAGO, ILLINOIS, ASSIGNOR TO RAILWAY UTILITY COMPANY, OF CHICAGO, ILLINOIS, A CORPORATION OF ILLINOIS.

RELAY.

1,282,426.

Specification of Letters Patent.

Patented Oct. 22, 1918.

Application filed November 1, 1913. Serial No. 798,652.

To all whom it may concern:

Be it known that I, LEE P. HYNES, a citizen of the United States, residing at Chicago, in the county of Cook and State 5 of Illinois, have invented certain new and useful Improvements in Relays, of which the following is a specification.

My invention relates more particularly to relays designed to carry comparatively small 10 currents and its object is to provide a device for this purpose which will be inexpensive to manufacture, durable and efficient and the more perishable parts of which may be readily replaced when worn out.

15 In the accompanying drawing, I have illustrated and in the following specification described in detail a preferred form of my invention but it is to be understood that the detailed disclosure is for the purpose of 20 exemplification only and that the scope of the invention is defined in the following claims in which I have endeavored to distinguish it from the prior art so far as known to me without, however, relinquishing 25 or abandoning any portion thereof.

In the drawing referred to above, Figure 1 is a central section through a preferred 30 form of my invention on the line 1—1 of Fig. 2; Fig. 2 a section on the line 2—2 of Fig. 1 at right angles to the plane thereof and Fig. 3 a section upon the line 3—3 of Fig. 1 at right angles to the plane thereof.

The same reference character is applied to each part wherever it occurs in the several views.

The particular form of the invention illustrated is designed more particularly for ready application to and removal from a switchboard, the frame or casing 4 of vulcanite or other suitable insulating material being provided upon opposite sides with pairs of connecting posts 6, 7, 8 and 9 which are adapted to be received by suitable resilient contact clips upon the switchboard upon 45 which the relay is to be used, and those numbered 7 and 8 respectively are connected up to the contacts of the device while those numbered 6 and 9 are connected to the terminals of the coil 10 of the relay magnet as seen more particularly in Figs. 2 and 3. It 50 will be noted that the terminals of each pair are arranged diagonally opposite each other as a result of which arrangement it is immaterial how the relays apply to the clips prepared for it upon the switchboard the proper

pair of terminals necessarily being applied to the proper pair of clips. Within the frame and secured thereto by screws 11, 11 is a U-shaped body of soft iron constituting a field for the magnet and the ends 12, 13 of the body are bent inwardly for a purpose to be presently stated. The transverse member of the field is perforated and tapped at 14 to receive the soft iron core 15 of the magnet. The coil 10 as shown 60 is wound upon a spool or sleeve 16 and provided with insulating end pieces 17, 18, the whole being adapted to be slipped over the core 15 of the magnet and within the loop of the body of soft iron above described. The armature 19 of the magnet is mounted upon the inwardly turned ends of the iron body by means of screw studs 20, 21 but is free to move longitudinally of the screws to and from the core of the magnet by reason of the fact that the heads of the screws are spaced away from the field to which they are attached as clearly shown in Fig. 1 of the drawing. Access to said screws may be had through openings 37, 38 in the 70 insulating casing as shown in Figs. 1 and 3.

Upon the upper end of the insulating casing is mounted a pair of brackets 21', 22, which as shown are struck up out of sheet metal and each secured at its ends by screws 23, 23, to the upper end of the casing, the intermediate portion of each bracket being offset or raised from the end of the casing to form a bridge. Bracket 21' supports the stationary contact 24 which as shown is of 80 a frusto-conical piece of graphite held in place in a similarly-shaped opening in the bracket by a plate 25 secured by screws 26. The other bracket 22 supports the movable contact being provided for this purpose with 85 depending screws 27, 28, upon which the flexible plate 29 forming the carrier for the movable contact, is loosely mounted. Screw 28 is somewhat longer than screw 27 permitting a greater movement to the contact carrier at this point and consequently an angular as well as a reciprocating movement to afford a greater separation of the contacts, and between the two screws a spring 30 is mounted in a cap screw 31 95 capped into the bracket 22. At its free end the contact carrier 29 is perforated to receive the frusto-conical contact 32 of copper or other suitable material and bent over beneath said contact to hold the latter in 100 105 110

place. The core 15 of the magnet is axially bored to receive a rod 33 of porcelain or other suitable insulating material which bears at one end against the armature 19 5 and at the other against the contact carrier 29 for operating the latter.

When the magnet is energized the rod 33 is forced by the armature against the movable contact carrier the first movement of 10 which is a substantially pivotal movement about the spring 30 to bring the contacts together. Any further movement of the carrier is taken up by the spring. The switch elements upon the upper end of the casing 15 are protected by a boxing of sheet metal, one element 34 of which comprising a top, end and two side walls, is secured to the insulating casing by inwardly turned flanges 36, 36, upon the side walls sliding into corresponding 20 grooves in the edges of the top member of the insulating casing (see Fig. 3). The second member of the boxing which constitutes the other end wall thereof is a plate 35 formed upon its ends with beads 36, 36, 25 which engage outwardly turned flanges upon the main boxing member as clearly shown in Fig. 2. If desired mica or other suitable insulating material may be secured to the inner walls of the boxing as a lining 30 therefor. The inclosure of the magnet and its armature is completed by the application of a pair of metal plates 37, 37', to the open sides of the frame where they are secured by screws or other suitable means. The inclosure is made absolutely dust proof by sealing the openings 37, 38 with wax.

The iron body surrounding the magnet coil forms with the core thereof and the armature a magnetic circuit which is open 40 only when the armature is away from the core and the gap in which even then is very narrow, thus forming a device which will operate satisfactorily with very feeble currents. The relay may be used in any position 45 desired and as is now apparent possesses all the advantages set out in the opening paragraphs of this specification.

I claim:

1. A relay of the character described comprising an electro-magnet having a longitudinal passage therethrough, a leaf armature at one end of the magnet, a rod extending entirely through the passage and loosely engaged by the armature, a movable and a 50 stationary contact at the other end of the magnet and movable means carrying the movable contact and engaged by the rod to operate the same.

2. A relay of the character described comprising an electro-magnet having a longitudinal passage therethrough, a leaf armature at one end of the magnet, a rod extending entirely through the passage and loosely engaged by the armature, a movable and a 60 stationary contact at the other end of the

magnet and resilient movable means carrying the movable contact and engaged by the rod to operate the same.

3. In a device of the class described, a coil, a U-shaped field partially surrounding the 70 coil, a core extending through the coil and connected at one end to the field, a pair of parallel studs mounted respectively upon the ends of the field on opposite sides of the axis of the coil respectively, an armature loosely mounted on the studs, an insulating casing surrounding the field and studs mounted on the casing and electrically connected to the coil.

4. In a device of the class described, a 80 magnet having a hollow core, an armature arranged to be drawn toward one end of said core, a rod extending through the core, a stationary contact adjacent the other end of the magnet, a movable member carrying a 85 contact at one end, a stud engaged by the movable member at the other end and a spring normally forcing said member into contact with the rod.

5. In a device of the class described, a 90 stationary contact, a movable contact, a member 29 carrying said movable contact and loosely mounted and reciprocable upon studs 27, 28, and a spring 30 intermediate 95 said studs and arranged to normally force the contacts apart.

6. A relay of the class described comprising an electromagnetic device and a switch operated thereby, two pairs of terminals for the device and switch respectively adapted 100 to engage clips upon a switchboard, the terminals of each pair being diagonally arranged upon the relay whereby the relay may be engaged with the clips upon the switchboard in either of two reverse positions without affecting the currents there-through.

7. In a device of the class described, a coil, a longitudinally bored core therefor, a leaf armature, studs upon opposite sides of the core upon which the leaf armature is loosely mounted and reciprocable, a rod resting loosely upon said armature and passing through the core, a switch on the opposite end of the magnet from the armature 115 thereof comprising a relatively stationary and a movable contact, a spring pressed member carrying the movable contact and arranged to be engaged and operated by the rod in opposition to said spring.

8. A relay comprising an electromagnetic coil, a core extending through said coil, a field attached to said core at one end and extending about the coil upon opposite sides thereof and having its terminals adjacent 125 the other end of the core, a pair of studs attached to the ends of said field, a leaf armature loosely mounted upon said studs, a rod resting upon said armature and extending through the core, a stationary contact upon 130

the end of the device opposite the armature, a spring-pressed member and a movable contact adapted to engage the stationary contact and carried by said member, said member being adapted to be engaged and operated by said rod, an insulated boxing surrounding said field, a pair of terminals for said coil arranged respectively upon opposite sides of said boxing and in diagonally opposite positions, a pair of terminals for said switch, also arranged upon opposite sides of said boxing and diagonal of the same, whereby the relay may be engaged with correspondingly arranged clips in either of two reversed positions without affecting the currents throughout the same. 15
